US0D1104011S

(12) **United States Design Patent** (10) Patent No.: **US D1,104,011 S**
 Cordova et al. (45) Date of Patent: ** Dec. 2, 2025

(54) **DISPLAY SCREEN OR PORTION THEREOF WITH GRAPHICAL USER INTERFACE**

(71) Applicant: **Google LLC**, Mountain View, CA (US)

(72) Inventors: **Jennifer Veneranda Cordova**, San Mateo, CA (US); **Vikram Padmakar Bapat**, San Francisco, CA (US); **Stephanie Shum**, Los Altos, CA (US)

(73) Assignee: **GOOGLE LLC**, Mountain View, CA (US)

(**) Term: **15 Years**

(21) Appl. No.: **29/875,506**

(22) Filed: **May 5, 2023**

(51) LOC (15) Cl. **14-04**

(52) U.S. Cl.

(57) **CLAIM**

The ornamental design for a display screen or portion thereof with graphical user interface, as shown and described.

DESCRIPTION

The sole FIGURE is a front view of a display screen or portion thereof with graphical user interface showing the new design.

The outermost dashed broken lines show an electronic device, which is environmental structure and forms no part of the claimed design. The dot-dash broken lines show a display screen or portion thereof and form no part of the claimed design. The remaining broken lines showing text and portions of the graphical user interface form no part of the claimed design.

1 Claim, 1 Drawing Sheet

Google search results for "folding bike" showing 14 results. The results are organized into a grid with 3 columns and 5 rows. The first row is a sponsored result for "Folding City Bike" with a price of \$300. The following four rows are organic search results for various folding bike models, each with a thumbnail image, product name, and price. The products listed are:

Product Name	Price
Recurse City Bike	\$300
Recurse Urban Hybrid Bike	\$300
5000 Step-Through Folding Bike	\$1,400
Pinion Folded 24-inch Bike	\$300
5000 Step-Through Folding Bike	\$1,400
5000 Step-Through Electric Bike	\$1,600
Recurse City Bike	\$300
Recurse Urban Hybrid Bike	\$300
White & Hybrid Electric Step-Through	\$1,600
Recurse Step-Through Bike	\$300
Recurse Step-Through Bike	\$300
Recurse Step-Through Bike	\$300

Generating bike options

When choosing a commuter bike, you can consider aspects like:

- Design: Bikes, road bikes, general bikes, and hybrid bikes are great for commuting.
- Material and durability: Baking-powdered cables offer better resistance and are good for bike durability.
- Suspension: A suspension fork reduces the impact from shocks and changes for a more comfortable ride.

Find a range of related items for five-fold accessories with filters:

1. **White & Hybrid Electric Step-Through**
Price: \$1,600
Description: This bike has a hybrid design. The frame is made of carbon and the wheels are made of aluminum. The frame is very light and the wheels are very strong. The bike has a hybrid motor and a hybrid gear system. The bike has a hybrid seat and a hybrid handlebar.

2. **Recurse Step-Through Bike**
Price: \$300
Description: This bike has a step-through frame. The frame is made of aluminum and the wheels are made of carbon. The frame is very light and the wheels are very strong. The bike has a hybrid motor and a hybrid gear system. The bike has a hybrid seat and a hybrid handlebar.

3. **Recurse Step-Through Bike**
Price: \$300
Description: This bike has a step-through frame. The frame is made of aluminum and the wheels are made of carbon. The frame is very light and the wheels are very strong. The bike has a hybrid motor and a hybrid gear system. The bike has a hybrid seat and a hybrid handlebar.
